CLAIM

The ornamental design for a portion of an inflatable amusement park as shown and described.

DESCRIPTION

FIG. 1 is a first top perspective view of a portion of an inflatable amusement park, according to our new design; FIG. 2 is a second top perspective view of the portion of an inflatable amusement park; FIG. 3 is a front elevational view of the portion of an inflatable amusement park; FIG. 4 is a rear elevational view of the portion of an inflatable amusement park; FIG. 5 is a top plan view of the portion of an inflatable amusement park; FIG. 6 is a left side elevational view of the portion of an inflatable amusement park; and,

FIG. 7 is a right side elevational view of the portion of an inflatable amusement park.
The broken lines in the figures are included for the purpose of depicting sections of the portion of an inflatable amusement park that form no part of the claimed design.

The undisclosed bottom surface of the portion of an inflatable amusement park forms no part of the claimed design.

1 Claim, 7 Drawing Sheets
